US0D1042711S

(12) **United States Design Patent** (10) **Patent No.:** **US D1,042,711 S**
(45) **Date of Patent:** **** Sep. 17, 2024**

(54) **FIREARM EXTENSION PLUG**

(71) Applicant: **22 Evolution LLC**, Columbia, MO (US)

(72) Inventor: **Joshua Thomas Yudys**, Columbia, MO (US)

(73) Assignee: **22 Evolution LLC**, Columbia, MO (US)

(**) Term: **15 Years**

(21) Appl. No.: **29/794,404**

(22) Filed: **Jun. 11, 2021**

(51) LOC (14) Cl. **22-01**

(52) U.S. Cl.

USPC **D22/108**
